COMBINED PULL AND ESCUTCHEON PLATE

John R. Morgan, Wheeling, Ill., assignor to Amerock
Corporation, Rockford, Ill., a corporation of Illinois

Filed Nov. 14, 1966, Ser. No. 4,658

Term of patent 14 years

(Cl. D10—3)

FIGURE 1 is a front view of a combined pull and escutcheon plate.

FIG. 2 is a perspective view of the combined pull and escutcheon plate.

FIG. 3 is a top view of the combined pull and escutcheon plate.

FIG. 4 is a side view as seen from the left of FIG. 1.

FIG. 5 is a sectional view taken along the line 5-5 in FIG. 2.

FIG. 6 is a sectional view taken along the line 6-6 in FIG. 5.

FIG. 7 is a sectional view taken along the line 7-7 in FIG. 5.

FIG. 8 is a sectional view taken along the line 8-8 in FIG. 5.

FIG. 9 is an enlarged sectional view taken along the line 9-9 in FIG. 4.

FIG. 10 is an enlarged sectional view taken along the line 10-10 in FIG. 4.

I claim:

The ornamental design for a combined pull and escutcheon plate, as shown.
